The ornamental design for a display screen with an animated graphical user interface, as shown and described.

DESCRIPTION

This design application is related to U.S. patent application Ser. No. 13/033,573, filed Feb. 23, 2011.

FIG. 1 is a front view of a first image in the sequence for a display screen with an animated graphical user interface, showing our new design;

FIG. 2 is a front view of a second image thereof;

FIG. 3 is a front view of a third image thereof;

FIG. 4 is a front view of a fourth image thereof;

FIG. 5 is a front view of a fifth image thereof;

FIG. 6 is a front view of a sixth image thereof;

FIG. 7 is a front view of a seventh image thereof; and,

FIG. 8 is a front view of an eighth image thereof.

The outermost solid line in all of the figures is the display screen.

The broken line showings of the control unit and various features of the graphical user interface are included for the purpose of illustrating environmental structure and portions of the article. The broken lines form no part of the claimed design.
